OVERHEAD SWITCHING SYSTEM

Raymond W. Donaldson, Lexington, and Warren J. Lewis, Mansfield, Ohio, assignors to The Ohio Brass Company, Mansfield, Ohio, a corporation of New Jersey

Application March 1, 1949, Serial No. 78,958

7 Claims. (Cl. 191—38)

1

This invention relates to trolley bus systems and in particular to systems for operating the frogs or switches at turn-outs from a station in the bus.

The object of this invention is to simplify the present systems of frog control by which the two or three contactors now required are reduced to the use of a single contactor and in which the frogs may be operated without interfering with the operation of the vehicle motors as for instance cutting off the power thereto in order to operate the frogs or closing the motor controller to operate the frog when it is not advisable to energize the motor.

The system also provides for continuous trolley wires and not wires in which there is an insulated section or a dead section, and further provides a system which does not require the skill of the vehicle operator in so positioning the bus that the current collector heads must engage the contactors in a certain manner in order to secure proper operation of the frogs.

This invention is an improvement with respect to the systems disclosed in a copending application, Serial Number 77,208, filed by the party Donaldson, February 18, 1949.

Fig. 1 shows our improved invention with the several members shown schematically.

Fig. 2 shows in partial section the current collector head shown schematically in Fig. 1.

Fig. 3 shows how the current collector head and the contactor, shown schematically in Fig. 1, cooperate.

Fig. 4 shows a top plan view of the operating mechanism of the frogs disclosed schematically in Fig. 1.

In Fig. 1 the system shows two main trolley wires 1 and 2, and branch wires 3 and 3' from the main wires respectively, and a trolley frog at each junction of a main and branch wire.

The frogs 4 and 5 are of the electrically operated mechanically reset type in which the electric operation of each frog is effected by a single coil 6 and 7 respectively which moves the pivotally mounted frog tongues 8 and 9 from a main line position to a branch position, and a mechanical reset mechanism including a latch 10 and 11 respectively whereby the tongues are returned to their main line position when the latch is engaged by a current collector head after passing tongues 8 and 9 respectively.

One form of a mechanically reset frog is disclosed in U. S. Patent 2,299,914 and also by the operating mechanism in Fig. 4 hereof. No claim is made for the construction of the type of frog

2

used in our improved system other than as one of the members of our improved system.

Positioned on the main trolley wire 1, fully in advance of the associated frog 4, is a contactor 12 with blades 12' which are electrically connected together (Fig. 3) but insulated from the trolley wire, and the contactor is connected to the coils 6 and 7 by the conductor 13 and the coils in turn are electrically connected to the trolley wire 2 either directly by the conductor 13' or through the medium of the frog 5.

Referring now to Fig. 4, the tongue operating mechanism for the reset frog is the same for both frogs 4 and 5 and is described with respect to frog 4 which comprises lever a secured to the frog tongue 8 by means of the pin a' to operate the tongue from either position to its other position when the lever a is moved.

The reset latch 10 is pivotally mounted on the cross member b' (Fig. 1) of the frog pan b (hidden in Fig. 4) and adjacent to the arm c of the frog pan, and a lever d is secured to the latch 10 by means of the pin d' whereby the latch 10 and lever d will move simultaneously when either is moved.

The levers a and d are pivotally connected adjacent their free ends to links e which have interposed therebetween a plunger or armature f, the movement of which in one direction is controlled by the single operating coil 6. The plunger f is reciprocally mounted in the coil 6.

The lever a is extended and its free end engages with the pivotally mounted spring held latch g which yieldingly holds the operating mechanism and tongue in either position. The reset latch 10 therefore has two positions as shown in Fig. 4 by the full (10) and dotted (10') lines. In Fig. 1 the reset latches 10—11 are shown only in one position corresponding to the setting of the tongues 8 and 9 respectively.

The tongues 8 and 9 are usually set for main line operation as shown in Figs. 1 and 4 and the operating coil of frogs 4 and 5 respectively may be connected in parallel as shown in Fig. 1 which in turn are electrically connected to the contactor 12 and to the trolley wire 2 of opposite polarity to that of trolley wire 1, or the coils may be connected in series as well known to those skilled in the art.

When the coil 6 (and 7) is energized the plunger f will be drawn to the right (Fig. 4) or to the left (Fig. 1) thereby moving the links e and in turn the free ends of levers a and d, and the tongues to their turn-out position, and the latch 10 to its reset position 10' (dotted lines Fig. 4).

Thus the latch 10 (and 11 of Fig. 1) will be engaged by the flange on a passing current collector and returned to its normal (full line) position and in so moving, the links and levers of the mechanism are moved and the tongue returned to the main line position, which takes place after the trolley head has passed the tongue.

It will be evident that the tongues are moved electrically from one position to their other position and returned to their first or normal position mechanically, as set forth in U. S. Patent 2,299,914, as previously stated.

The trolley bus B is provided with a motor 14 and controller 15 therefor. The bus is also provided with a pair of trolley poles 16 and 17, each with a current collector head X or Y respectively, hereinafter described, mounted on the upper end of the trolley poles and each head provided with a current collector 18 or 19 respectively, as per Fig. 1.

One head X is provided with metallic ring-like connecting means 20 which is insulated from the associated current collector head and current collector, and it is this connecting means 20 which engages the blades 12' of the contactor and energizes the same, whereby the operating coils of the frog operating mechanism are energized to effect operation of the said mechanism and move the frog tongues regardless of the lateral movement of the bus relative to the trolley wires at the time the connecting means engages the contactor.

The bus is equipped with circuits, one for controlling the motor operation and the other for controlling the operation of the frogs by first energizing the contactor 12. The motor circuit is controlled by the controller 15 and the frog operating mechanism is controlled by a normally open but manually closable switch 21, as to movement of the frog tongues from their normal position.

The switch 21 including the holding and releasing means is disclosed in the co-pending application of Donaldson before referred to, Serial Number 77,208, filed February 18, 1949; hence, applicants do not herein claim the originality of the same.

The switch 21 may be of the push-button type and is provided with two connecting bars 22 and 23 and with a holding and releasing mechanism including catch 24 and a yieldable latch 24' to hold the switch 21 closed after being manually closed, until the coil 25 is energized to automatically effect release of the connecting bars 22 and 23 from their closed position.

The holding and releasing mechanism is so constructed that when the switch is operated to its closed position, the latch 24' will be momentarily depressed against spring 24'' as a result of the engagement of the catch 24 with the latch 24' and when the catch has passed the latch 24' the latch will spring back and engage the catch 24 on its opposite side from that shown and remain so until the coil 25 is energized thereby retracting the latch and releasing the switch.

The switch 21 is provided with a dash-pot mechanism 25' or other retarding mechanism which normally holds the switch open and effects slow opening of the switch after the coil 25 is energized and the holding mechanism released.

The motor control circuit consists of the conductor 26 from the current collector 18, controller 15, motor 14, and conductor 27 which connects to the current collector 19.

The contactor energizing circuit consists of the

conductor 26 from current collector 18, conductor 28, coil 25, bar 22, and conductor 29 which connects to connecting means 20.

It will be noted that the current collector 18 and the connecting means 20 are of the same polarity, hence there is no danger of a short circuit occurring between those two elements at any time, which is an improvement over the co-pending Donaldson application already referred to.

By introducing the switch 21 into the circuit to control the energization of the contactor, control of the movement of the frog tongues is accomplished by the operator from a station in the bus and he is free to close the switch 21 at any time before the connector engages a contactor if he wishes to change the position of the frog tongues. The switch 21 will remain closed until the connecting means engages the contactor and may be arranged to remain closed for a time thereafter on account of the retarding action of the dash-pot 25', which permits the coils 6 and 7 to receive energizing current for a time after the initial engagement between the connecting means and the contactor as the bus moves forward. The use of the retarder 25' is optional.

If the operator does not wish to change the position of the frog tongues, he merely proceeds without closing the switch 21.

To notify the operator that the switch is closed, the signal light 30 or other means may be employed. The light is shown as connected to the conductor 28 by the switch bar 23 and to the conductor 27 with a resistance 31 in series as the line potential is usually about 600 volts and the lights are made for much lower voltage.

The system above described requires no cutting or breaking the continuity of the trolley wires at or adjacent the contactor 12 or of depriving the motor of current at any time the frog operating circuit is closed, the two circuits acting independently.

It is not necessary to pre-position the bus with respect to the contactor so long as the current collector heads remain in position on the trolley wires and the only requirement is for the bus operator to close the switch 21 prior to the connecting means engaging the contactor.

We use the same current collector or trolley head as disclosed in the aforesaid co-pending Donaldson application and make no claim therefor and the same is disclosed herein in Figs. 3 and 4, and shown schematically in Fig. 1.

The head comprises a bowl-shaped member 32 shown as formed preferably of sheet metal and having an inner portion 33 and an outer portion 34 with a projecting portion 35 to receive the end of the trolley pole 16 whereby the head is supported. Insulation 36 is interposed between the member 35 and pole 16 which not only insulates the head electrically from the pole but absorbs vibration.

Mounted on the member 32 is a substantially vertical stud 37 with a flaring upper end having an inner concave spherical bearing surface 38 and an outer spherical bearing surface 39 parallel to the surface 38. Mounted on the surface 38 is the current collector 18 with a spherical portion mounted on and conforming to the bearing surface 38 and provided with a groove 40 for the trolley wire 1.

To hold the current collector 18 in place, a circular member 41 is provided with a lip which engages the outer spherical bearing surface 39 and having oppositely disposed openings to receive the screws 42. This secures the current

collector 18 (Fig. 1) to the head X so that the current collector may rotate in a plane substantially at right angles to the longitudinal axis of the stud 37 which is a plane corresponding under normal operation to the plane of the contactor blades 12'; the member 41 is provided with a transverse slot 43 parallel to the groove 40 which permits the current collector to swivel in a plane corresponding substantially to the said axis of the stud 37.

The head X is provided with a metallic ring-like connecting means 20 surrounding the head and insulated from the members 33 and 34, hence from the head by the insulating means 44 and both the connecting means 20 and the insulating means 44 are supported by the bowl-shaped member 32. The portion 33 is formed with a flange 45 which when pressed into place against the insulating means 44 insures the parts 20 and 44 moving with the head.

The metallic ring-like connecting means 20 projects only a sufficient amount from the head to insure its engaging the contactor blades 12' (Fig. 3) without interfering with the overhead in case of dewirement. The conductor 29 connects to the connecting means 20 and the conductor 26 to the head 32.

The head Y is of the same construction as the head X but with the members 20 and 44 omitted.

Fig. 3 shows an end view of the collector head passing through the contactor 12 and shows the engagement between the blades 12' and the collecting means 20.

What we claim as new and desire to protect is seen further in the following claims.

1. In a control system for a pair of trolley frogs each provided with a tongue operable to two positions and positioned at the junction of a pair of trolley wires of opposite polarity in an overhead system, a branch trolley wire from each main wire, in combination, a contactor associated with one of the main trolley wires in spaced and insulated relation thereto, connecting means associated with a current collector on an electrically operated vehicle and arranged to engage the contactor, electric operating means for the frogs connected between the contactor and the other trolley wire and operable to change the normal setting of the frog tongues to their other position, a motor control circuit on the vehicle and a second control circuit on the vehicle including a normally open manually closable switch provided with means to hold the switch closed until the connecting means engages the contactor and time delay mechanism to retard the rate of opening of the switch after the connecting means engages the contactor, the last said control circuit connecting the said connecting means and the associated current collector whereby the polarity of the connecting means and of the current collector will be the same and the same as the main trolley wire with which the contactor is associated and further the contactor will be energized at the same polarity as the main wire with which the contactor is associated when the connecting means engages the contactor while the control switch is closed.

2. The combination set forth in claim 1 and the combination therewith of electrically controlled means associated with the holding means to automatically release the switch holding means when the connecting means engages the contactor.

3. The combination set forth in claim 1 in

which the motor control circuit and the second control circuit are so related that they are operably independent of each other and unaffected by the energization of the other.

5. 4. A control system for a pair of trolley frogs provided with guide tongues movable to either of two positions and located at the intersection of a pair of main and branch trolley wires comprising, a contactor associated with one of the main trolley wires and wholly in advance of the frogs and insulated from the trolley wire, connecting means associated with one of a pair of current collectors in insulated relation thereto and arranged to engage the contactor, the current collectors mounted on an electrically operated trolley bus, combined electrically and mechanically operable means to actuate the frogs, the electrically operable means connected to the contactor and to the other main trolley wire, the electrical and the mechanical frog actuating means are each operable to change the position of the tongues to opposite positions, a motor control circuit and a frog control circuit independent of the motor control circuit, both circuits associated with the trolley bus and the circuits provided with independent control switches, the frog control circuit electrically connecting the said connecting means to the associated current collector when the frog control switch is closed whereby the connecting means will be energized to the same polarity as the associated current collector and the contactor will be energized accordingly when engaged by the connecting means and the frog control switch is closed, the said control circuits and switches being so connected and related that they are energizable independently of each other and each circuit unaffected by the energization of the other circuit, the switch for the frog control circuit being normally open and manually closable, the frog control switch provided with holding means to hold the switch closed when manually closed, the holding means provided with actuating means to release the switch from its closed position when the connecting means engages the contactor.
5. A control system for a pair of trolley frogs provided with guide tongues movable to two positions and positioned at the intersection of a pair of main and branch trolley wires, the main trolley wires being of opposite polarity comprising, a contactor associated with one of the main trolley wires in spaced and insulated relation to the trolley wire and a connecting means associated with one of a pair of current collectors mounted on an electrically operated trolley coach to engage the contactor, electrically operable means for the frogs electrically connected to the contactor and to the other main trolley wire and operable to change the position of the frog tongues from their normal position to their other position, a motor control circuit and a frog control circuit, both circuits associated with the coach and non-affected by the energization of the other circuit and each circuit provided with a separate control switch whereby the circuits may be energized independent of the other circuit, the switch for the frog control circuit being normally open and manually closable and provided with releasable holding means to maintain the switch closed after manually closing and electrically controlled means associated with the holding means to release the holding means when the connecting means engages the contactor whereupon the control switch returns to its normal open position, the frog control circuit elec-

trically connecting the said connecting means and the associated current collector whereby the connecting means will be energized according to that of the current collector and the same as the main trolley wire associated with the contactor and the contactor will be energized and have the same polarity as that of the associated trolley wire when the connecting means engages the contactor while the control switch in the frog control circuit is closed.

6. The combination in a control system for a trolley frog provided with electrically operable means to control the movement of the frog tongue to one position and mechanically operable means associated with the electrically operable means to effect the return of the frog tongue to its first position, of a contactor, a connecting means on a current collector head mounted on an electrically operable bus, the connecting means being insulated from the current collector head and arranged to engage the contactor, a pair of independently functioning control circuits on the vehicle, one circuit controlling the energization of the vehicle motor and the other circuit controlling the energization of the connecting means from the associated current collector, independently operable and normally open switch means in each control circuit and operable from a sta-

tion in the vehicle to control the energization of either circuit independently of the other, and mechanically controlled holding means to maintain the switch means for the said other circuit closed after being closed by the vehicle operator until the connecting means engages the contactor, electrically controlled means associated with the holding means to effect release of the holding means when the connecting means and the contactor engage.

7. A control system constructed according to claim 6 having in combination therewith, means to delay the opening of the frog control switch for a predetermined time after the connecting means engages the contactor.
